CONTAINER CLOSURE

Herbert A. Barnby and Jack M. Wheaton, Toledo,
Ohio, assignors to Owens-Illinois Glass Company,
a corporation of Ohio

Application May 1, 1943, Serial No. 485,320

4 Claims. (Cl. 215—38)

Our invention relates to caps or closures for jars, bottles and other containers. An object of the invention is to provide a novel and practical cap for closing and hermetically sealing a container to which it is applied. The invention provides a cap which is particularly adapted for use with jars or other containers in which foodstuffs are packed and sealed by processes which result in forming a partial vacuum within the container. Such a vacuum process is extensively used in canning fruits, vegetables, and the like, in which process the jars are filled and the caps applied while the material is at a high temperature, so that as the contents of the jar cools, the steam or vapor is condensed and produces a partial vacuum.

An object of our invention is to provide a cap which is readily applied to the jar and makes an effective and permanent seal.

A further object of the invention is to provide a cap of the character indicated which is adapted for use with various styles of jar tops or finishes, and which does not require any special fastening means for securing the cap.

A further object of the invention is to provide such a cap which may be readily and repeatedly applied to and seal the container independently of any vacuum, so that when only a part of the contents is dispensed at a time, the remaining portion may be resealed until needed.

A further object of the invention is to provide a cap or closure of the character indicated which is made of inexpensive materials which are readily available and which serve as an efficient substitute for the usual metal caps.

Other objects of the invention will appear hereinafter.

Referring to the accompanying drawing:

Fig. 1 is a fragmentary sectional elevation of a glass jar with a cap placed in position thereon.

Fig. 2 is a similar view but with the cap bowed downwardly owing to the partial vacuum within the jar.

Fig. 3 is a view similar to Fig. 2, but with the thickness of the various layers of material forming the cap, greatly exaggerated for the purpose of illustration.

Fig. 4 is a fragmentary view on a larger scale, of a portion of the cap as applied to the jar.

Fig. 5 is a diagrammatic plan view of the cap with the layers of material progressively broken away.

The closure device or cap C is shown applied to a glass jar J having a neck 6 formed with an

external spiral bead or screw thread 7 adapting the jar for use with a screw-threaded cap or ring.

The cap is of laminated construction comprising superposed layers or disks of suitable material bonded together by layers of adhesive. The cap as shown has an inner layer 11 of wax, applied to the under surface of a layer or disk of oil paper 12, a layer of pulpboard 14 overlying the disk 12 and secured thereto by an interposed layer 13 of adhesive material, a layer 16 of kraft paper or the like overlying the pulpboard and bonded thereto by a layer 15 of adhesive. The uppermost section or layer of the cap provides a cap shell which comprises a disk 20 of kraft paper or the like formed with a skirt 21 which surrounds the subjacent laminations and extends downwardly into position to surround the bead 7, such bead serving to hold the cap centered on the jar. An inner layer 18 of jute paper is bonded to the kraft paper 20 by an interposed layer 19 of adhesive and provides a lining for the cap shell. A layer 17 of adhesive material is provided between the laminations 18 and 16. It will be seen that the laminations comprised in the cap are bonded together by adhesive in a manner to form an integral or one-piece cap.

The layer 11 is a sealing material preferably of an amorphous petroleum wax, which at the temperatures to which it is subjected during the vacuum sealing operations, is of a consistency adapting it to making an effective seal, and which at normal living room temperatures remains sufficiently soft and plastic to make a good seal when applied with a slight pressure to the container. The cap is thus adapted to be repeatedly applied to the container and make an airtight seal when applied at normal living room temperatures. The petroleum wax may have added thereto, a small percentage of any suitable viscous material which increases the adhesive qualities of the wax and prevents crystallization at low temperatures. We have found that a small percentage of the commercial product known as "Vistac No. 2" added to the petroleum wax is satisfactory for this purpose, such product being a synthetic hydrocarbon of the polybutene type having a molecular weight of approximately 6000.

The layer 12 of oil paper, being nonporous and impervious to moisture, cooperates with the layer 11 of wax to make a reliable and permanent seal. The disk 14, preferably consisting of a firm pulpboard of substantially greater thickness than the adjoining layers of paper, serves to stiffen and strengthen the cap as a

whole. We have found that a thickness of .05 inch gives satisfactory results. The kraft paper lamination 16 is comparatively thin but provides a strong, tough, flexible layer which greatly adds to the strength of the cap.

The cap shell which comprises the kraft paper 20 and its inner lining 18 of jute bonded thereto by the layer 19 of adhesive, serves to strengthen the cap as a whole and increases its resistance to bending stresses. It offers effective resistance to the bowing downward of the cap under atmospheric pressure when a partial vacuum is formed within the container, and thus prevents excessive deformation or bowing of the cap.

Modifications may be resorted to within the 15 spirit and scope of our invention.

We claim:

1. A cap for closing and sealing a container, comprising superposed laminations including an inner layer of wax which is soft and plastic at normal living room temperatures, a superposed lamination of oil paper, a lamination of pulpboard overlying the oil paper and bonded thereto by a layer of adhesive material, a paper cap shell overlying the pulpboard and formed with a marginal skirt surrounding said laminations and extending downwardly therebelow, and means for bonding said shell to the pulpboard, the lamination of pulpboard being of substantially greater thickness than the adjoining layers of paper and the cap as a whole being sufficiently soft and flexible to permit a substantial downward flexing or bowing under atmospheric pressure when the cap is seated on and sealed to a vacuumized container.

2. A cap for closing and sealing a container, comprising superposed laminations including an inner layer of wax which is soft and plastic at normal living room temperatures, a superposed lamination of oil paper, a lamination of pulpboard overlying the oil paper and bonded thereto by a layer of adhesive material, a cap shell overlying the pulpboard and formed with a marginal skirt surrounding said laminations and extending downwardly therebelow, and means for bonding said shell to the pulpboard, the pulpboard lamination being of greater thickness than the adjoining layers of paper and the cap as a whole being sufficiently soft and flexible to permit a substantial downward flexing of the cap under atmospheric pressure when the cap is

5 seated on the vacuumized container, said shell comprising an outer layer of kraft paper, an inner lining of jute paper, and a layer of adhesive bonding said jute paper to the kraft paper, said shell providing means for strengthening the cap and effectively limiting the degree of said downward flexing.

3. A cap for closing and sealing a container, comprising superposed laminations including an inner layer of wax which is soft and plastic at normal living room temperatures, a superposed lamination of oil paper, a lamination of pulpboard overlying the oil paper and bonded thereto by a layer of adhesive material, and a cap shell comprising a sheet of kraft paper overlying the pulpboard and formed with a marginal skirt surrounding said laminations and extending downwardly therebelow, a lamination of kraft paper interposed between said pulpboard and the cap shell, and layers of adhesive material interposed between and bonding together the pulpboard and said lamination of kraft paper and between and bonding together the said kraft paper and said cap shell, the thickness of the pulpboard lamination being of the order of .05 inch and the adjoining layers of paper of substantially less thickness than the pulpboard, the cap as a whole being fortified by the cap shell against excessive deformation or bowing when subjected to the suctional action of a partial vacuum within the container.

4. A cap providing a closure for containers, said cap being of laminated construction comprising superposed laminations consisting respectively of kraft paper, jute paper, kraft paper, pulpboard, and oil paper in the order mentioned, with interposed layers of adhesive material between said laminations and bonding them together, the outer lamination of kraft paper serving as a cap shell and being formed with an integral marginal skirt surrounding said other laminations, the thickness of the pulpboard lamination being of the order of .05 inch and the adjoining layers of paper of substantially less thickness than the pulpboard, the cap as a whole being fortified by the cap shell against excessive deformation or bowing when subjected to the suctional action of a partial vacuum within the container.
